APPARATUS FOR SEPARATING METALS
AND ALLOYS

William B. Cohen, Elizabeth, N. J.

Application January 31, 1940, Serial No. 316,487

8 Claims. (Cl. 266—33)

This invention relates to an apparatus for reclaiming metals and, more particularly, to an apparatus for separating metals or alloys of a low melting point from metals or alloys of a comparatively high melting point.

Formerly, in apparatus for reclaiming metals, the metals were not subjected to heat until they had entered the furnace. The metals, therefore, had to travel a great distance in the furnace at a slow rate before the one having the lower melting point reached a molten state. The mechanism for dislodging the molten metal or alloy from the non-molten metal or alloy in such apparatus was complex and had a mild reciprocating, slow agitating or sliding action, it being necessary that the material be passed slowly thereby through the furnace, so that the metal having a low melting point would have sufficient time to become molten and dislodged from the metal having a high melting point.

It is an object of the present invention to provide an apparatus for separating metals or alloys of a low melting point from those having a high melting point, in which the metal is heated before entering the furnace by the same source of heat as is used for heating the furnace, the metal or alloy of low melting point reaching the interior of the furnace in molten state.

Another object of the invention is to provide a high-speed agitating mechanism for such an apparatus which is simple in construction and which will quickly separate the molten metal from the non-molten metal and impart movement to the non-molten metal allowing the same to pass through the furnace at a comparatively high rate of speed.

A still further object of this invention is to provide a metal separating apparatus in which the heat is generated above the shaker trays on which the metal travels so that the heat is concentrated where needed, which results in a saving of time in bringing the furnace up to the proper temperature and also in a saving of fuel because only the upper part of the furnace is heated.

Another object of the present invention is to provide a furnace in which the shaker trays may be easily and quickly changed.

Still another object of the invention is to provide an apparatus for separating metals or alloys having a comparatively low melting point, which apparatus is simple and economical to construct and which occupies a comparatively small area.

Other objects of the invention will become ap-

parent in the course of the following specification.

The above and other objects of the present invention may be realized by providing a frame supported upon legs, the upper section being covered by a hood lined with refractory cement. In the upper portion of the discharge end of the apparatus is mounted a combustion chamber which is supplied with suitable burners. At the opposite or feeding end of the apparatus, also in the upper portion and substantially in alignment with the combustion chamber, is a feed box having a vertically adjustable perforated gate through which heat penetrates into the feed box. The feed box is pivotally mounted at its outer end, the inner end extending into the furnace and engaging the upper end of a shaker tray which slopes toward the discharge end of the furnace. Another shaker tray, sloping toward the discharge end of the furnace, is also provided. The trays are mounted in cascade relation to one another, so as to provide a drop between them. The trays rest on polygonal-shaped cams on drive shafts extending transversely of the furnace which are driven through a suitable drive. The combustion chamber and burners are located above the bottom surface of both trays, so that the heat is directed over the top surface of them. The bottom portion of the furnace is preferably left open, so that the molten metal may drop to the floor and also so that the trays may be easily removed and new ones or ones having different sized screening may be substituted. A receptacle for the molten metal could, of course, be placed on the floor under the screens, if desired.

The invention will appear more clearly from the following detailed description when taken in connection with the accompanying drawings, showing by way of example a preferred embodiment of the invention.

In the drawings:

Figure 1 is a plan view of the apparatus of this invention, the furnace chamber being partly broken away;

Figure 2 is a longitudinal sectional view taken on the line 2—2 of Figure 1.

Figure 3 is an end view in elevation of the feed end of the apparatus, taken on the line 3—3 of Figure 2;

Figure 4 is a detail view of the same arrangement on the drive shaft taken on the line 4—4 of Figure 1; and

Figure 5 is a detail view of the yoke on the un-

derside of the shaking trays taken on the line 5—5 of Figure 1.

Like numerals refer to like parts throughout the several views.

The apparatus of this invention comprises a substantially semi-cylindrical hood 10, preferably of sheet steel 11, which is lined with a refractory cement 12. The hood 10 forms a furnace chamber 18, closed at both ends, the bottom side of which is open. The hood 10 is mounted on a rectangular-shaped frame having parallel side members 13 and 14 connected by parallel end members 15 and 16, the rectangular frame being in turn supported by legs 17.

The discharge end of the chamber 18 is designated by the reference numeral 19, and the feed end of the chamber is designated by the numeral 20.

In the discharge end 19 of the chamber 18 is a combustion chamber 21 in communication with the chamber 18 through an opening 22. The opening 22 is located in the upper portion of the hood 10. Suitable burners 23 and 24, which may be designed to burn gas, oil or any other suitable fuel, cooperate with the combustion chamber 21.

In the lower portion of the discharge end 19 of the chamber 18 is a discharge opening 25 through which the unmelted metal may be discharged, as will hereafter be more fully described.

At the feed end 20 of the chamber 18 is an opening 26 through which the metal is fed into the chamber 18. The opening 26 is located in the upper portion of the feed end 20 of the chamber 18 and is opposite to the combustion chamber 21, the bottom of said opening being in substantial alignment with the bottom of the opening 22, so that the heat from the combustion chamber will be directed toward the opening 26.

Cooperating with the opening 26 is a feed box 27 having sides 28 and 29, and a back 30. The front of the feed box comprises a vertically sliding gate 31 which is guided in its vertical movement in grooves on the opposite sides 28 and 29. The gate 31 has perforations 32 therein in order that heat from the combustion chamber 21 will enter the feed box. The gate 31 is adjustable vertically, so that the opening between the bottom of the gate and the bottom of the feed box may be varied in accordance with the different size pieces of metal which are to pass therethrough and to regulate the rate of feed of the metal into the chamber 18. The bottom 33 of the feed box 27 is inclined from front to rear, the said bottom having an extension 34 extending through the opening 26 into the chamber 18, so that the metal in the feed box will travel down an incline into the chamber 18.

The feed box 27 is pivotally mounted at the back thereof to a support 35 projecting rearwardly from the end 20 by means of lugs 36 and 37 on the underside of said feed box. The lugs 36 and 37 movably engage a cross rod 38 which is mounted on the support 35. The cross rod 38 may be raised or lowered to change the angularity of the bottom of the feed box by placing the opposite ends of the rod in recesses 39 in the walls of support 35 on opposite sides of the feed box, corresponding recesses 39 being in alignment with one another.

The extension 34 of the bottom 33 rests upon an angle bar 40 and the back 41, to which the bar 40 is connected, of a rectangular shaped shaker

tray 42. The tray 42 has opposite parallel sides 43 and 44 and a screen-mesh or perforated-plate bottom 45. The front end of the tray is open. The bottom of the shaker tray 42 is inclined from front to rear so that pieces of metal entering from the feed box 27 will travel down an incline toward the discharge end of the chamber 18.

The back of the tray 42 rests upon polygonal-shaped cams 46 and 47 on opposite ends of a drive shaft 48 that extends transversely of the chamber 18. The cams 46 and 47 engage reinforcing plates 49 and 49a, respectively, fastened to the underside of the opposite sides 43 and 44.

The cams 46 and 47 are preferably square but may be rectangular or any other polygonal shape, so that upon rotation of the shaft 48 the edges formed by the meeting of adjacent sides of the cam will raise the tray 42 vertically and also impart a longitudinal movement to the tray.

On the drive shaft 48, adjacent the sides 43 and 44 of the tray 42, are discs 50 and 50a which prevent lateral movement of the tray.

The opposite ends of the drive shaft 48 are mounted in bearings 51 and 52 resting on pedestals 53 and 54, respectively. The shaft 48 may be raised or lowered, so that the angularity of the bottom of the tray 42 may be increased or decreased by placing shims between the bearing and the pedestal or removing shims as the condition may require.

A sprocket 55 is fastened to the drive shaft 48, which sprocket is driven by a chain 56 engaging a sprocket 57 on another drive shaft 59 which extends transversely of the chamber 18 adjacent the forward end of the tray 42 in a horizontal plane lower than that of the horizontal plane of the shaft 48.

The drive shaft 59 has polygonal-shaped cams 60 and 61 on which the forward end of the opposite sides 43 and 44 of the tray 42 rest. A movement similar to that imparted to the tray 42 by rotation of the cams 46 and 47 also is imparted by the cams 60 and 61.

Opposite ends of the drive shaft 59 are mounted in bearings 63 and 64 on pedestals 65 and 66, respectively. Discs 67 and 68 are mounted on the shaft 59 adjacent the outer surface of the sides 43 and 44 to prevent lateral movement of the tray.

Mounted on the underside of the tray 42 at the forward end thereof adjacent the shaft 59 are yokes 69 and 70. These yokes fit loosely about the shaft 59, as shown more particularly in Figure 5 of the drawings, which allows a longitudinal movement of the tray 42 and also limits the extent of this movement.

Elongated openings 71 and 72 are cut in the side of the hood 10 in order to facilitate the mounting of the shafts 59 and 48, respectively.

The drive shaft 59 has fastened thereon a sprocket 73 which is driven by means of a chain 74 which cooperates with a sprocket 75 mounted on a drive shaft 76.

The shaft 76 is in a horizontal plane lower to that of the drive shaft 59 and is mounted forward of the shaft 59. The opposite ends of the shaft 76 rest in bearings 77 and 78 mounted on pedestals 79 and 80. The shaft may be raised or lowered by placing shims under the bearings.

Cams 81 and 82, similar to the cams 56 and 47 and 60 and 61, are mounted on the shaft 76 and are adapted to bear against the underside of opposite sides 83 and 84, respectively, of a rec-

tangular shaped shaker tray 85. The underside of the sides adjacent the cams may be reinforced by wearing plates.

The tray 85 is positioned below the tray 42, the rearward end 86 thereof extending under the forward end of the tray 42, the forward end thereof extending through the discharge opening 25. The bottom 87 is in the form of a wire mesh or perforated plate and extends slightly beyond the sides of the tray 85 at the forward end. The forward end of the shaker tray 85 is open.

The bottom 87 is inclined at an angle from the front thereof, at the discharge end of the chamber 18, toward the rear 86 of the tray. The trays 42 and 85, therefore, bear a cascade relationship to one another.

The metal pieces from the feed box 27 will travel down an incline dropping from the extension 34 onto the tray 42 and dropping from the tray 42 to the tray 85.

Yokes 89 and 90 are fastened to the underside of the tray 85 adjacent the shaft 76 and fit loosely over said shaft, which allows a slight longitudinal movement and at the same time limits the extent of this movement.

The drive shaft 76 has another sprocket thereon designated by the reference numeral 91, which is driven by means of a chain 92 engaging a sprocket 93 on a drive shaft 94 which extends transversely of the chamber 18 at the forward end of the tray 85, the shaft 94 being in a horizontal plane lower than the horizontal plane of the shaft 76.

The shaft 94 rests in bearings 95 and 96 on pedestals 97 and 98, respectively. Polygonal-shaped cams 99 and 100 bear against reinforcing plates 101 and 102, respectively, on the underside of the sides 83 and 84 of the tray 85.

Discs 103 and 104 mounted on the shaft 94 at the outer surface of the sides 83 and 84, and discs 105 and 106 mounted on the shaft 76 likewise on the outer surface of the sides 83 and 84, respectively, prevent lateral movement of the tray 85.

Mounted on the shaft 94 is another sprocket 107 which is connected by a chain 108 to a sprocket 109 on a motor M which serves as a source of power to drive the various drive shafts 94, 76, 59 and 48. A stack 110 is located at the feed end of hood 10 and communicates with the chamber 18.

The operation of the apparatus is as follows:

Heat is introduced into the chamber 18 from the combustion chamber 21 through the opening 22, the chamber 21 being in the upper part of the discharge end of the chamber 18. The heat is directed toward the opening 26 in the upper portion of the feed or intake end 28 of the chamber 18 where it enters the feed box 27 through the perforated gate 31. It will be noted that the heat is above the shaker trays 85 and 42.

The combustion gases travel through the furnace and leave the chamber 18 by the stack 110 which is located at the feed end of the chamber.

When the metal having the lower melting point in the forward part of the feed box 27 reaches a molten state, the mechanism for operating the shaker trays is set in motion by starting the motor M. The motor M, through the sprocket 109 on the drive shaft thereof, drives the sprocket 107 by means of the connecting chain 108. This rotates the shaft 94 which, in turn, revolves the sprocket 93 thereon, driving the sprocket 91 on the shaft 76 by means of the connecting chain 92. Rotation of the shaft 76 turns the sprocket 75

75 which revolves the sprocket 73 on the shaft 59 through the connecting chain 74, which turns the sprocket 57 also mounted on the shaft 59. The revolving of the sprocket 57 drives the shaft 48 by means of the chain 56 which is connected to the sprocket 55 on the shaft 48.

Upon rotation of the shaft 94, the edges formed by the adjoining surfaces on the cams 99 and 100 raise the forward end of the tray 85 vertically, the same being dropped vertically when the flat surface of the cam engages the reinforcing plate on the underside of the opposite sides 83 and 84 of the trays. A slight longitudinal movement is imparted to the tray 85 as the edges formed by the joining of the surfaces of the cams engage the reinforcing plates during the rotation of the shaft 94.

A like action takes place simultaneously at the rearward end of the tray 85 where the cams 81 and 82 impart the same movement to the rearward end of said tray as the cams 99 and 100 impart to the forward end thereof. The yokes 89 and 90 attached to the bottom of the tray 85, adjacent the shaft 76, are loosely mounted thereover and limit the longitudinal movement imparted to the tray by the engagement of the edges of the cams on the shafts 94 and 76 with the bottom of the tray.

In this manner, a vertical as well as longitudinal movement is given the shaker tray 85. A vigorous high-speed, up and down jumping action is imparted to the tray 85, since, for example, if square cams are used, the tray 85 will raise and drop four times to each revolution of the shafts 94 and 76. The shafts 94 and 76 would normally revolve at 150 revolutions per minute, the tray 85 thereby receiving 600 vigorous, up and down movements per minute. The number of times the tray will be raised and dropped per revolution of the shaft may be varied in accordance with the shape of the cams. The intensity of the bump may be regulated also by varying the size of the cams.

A movement similar to that imparted to the shaker tray 85 is also imparted to the shaker tray 42. Rotation of the shaft 59 will turn the cams 60 and 61. The engagement of the edges formed by adjoining surfaces of the cams with the bottom of the tray 42 will raise the forward end of said tray, the same being dropped to engage the surface of the cam. The rearward end of the tray 42 is likewise simultaneously given an up and down, vertical movement by rotation of the cams 46 and 47 on the shaft 48.

Up and down movement of the tray 42 imparts a vibrating movement to the feed box 27, since the extension 34 of the bottom of the feed box at the front thereof rests upon the angle bar 40 on the end of the tray 42 and the rearward end of the feed box is pivoted to the rod.

The vibrating movement of the feed box 27 will cause the metal to move down the inclined bottom thereof over the extension 34 and onto the bottom 45 of the tray 42. Since the heat from the burner penetrates into the feed box across the extension 34, the metal having the lower melting point is already molten by the time it travels down the feed box extension and enters the furnace. The same reaches the shaker tray 42 in a molten state.

The vigorous, high-speed, up and down bumping action of the tray 42 will separate the molten from the unmolten metal, the molten metal dropping through the screen or perforated bot-

tom 45 onto the floor below the chamber 18 or into a receptacle placed on said floor.

The use of an open bottom to said chamber allows the molten metal to flow freely from the screen, there being no passages between the screen and the floor which may become clogged with foreign substances.

The movement imparted to the shaker tray 42 by the cams on the shafts 48 and 59 will cause the non-molten metal to move toward the discharge end of the chamber 18 down the inclined bottom of the tray 42. From the tray 42, the metal will drop onto the shaker tray 85 where the metal will be again vigorously agitated. Any molten metal which has adhered to the non-molten pieces will be loosened by this agitation and will drop through the wire mesh or perforated bottom 87 of the tray, the molten metal dropping onto the floor or into a receptacle under the chamber 18. The non-molten metal will pass down the inclined bottom of the tray 85, due to the action of the cams on the shafts 94 and 76, and through the discharge opening 25, from which it will be discharged from the chamber 18.

It will be noted that, at all times while the metal is passing through the chamber 18, the heat from the combustion chamber 21 is applied thereto from the top of the furnace, so that the metal of a low melting point will be maintained in a molten state while it passes through the furnace, in order that the metal of a low melting point may be separated from the metal of a high melting point by the action of the shaker trays 42 and 85. Heat being applied to the upper side of the trays will also allow the molten metal to cool as it drops from the trays to the floor or container thereon.

It will also be noted that it is possible with the construction of the furnace of this invention to readily remove the trays 42 and 85 from the chamber 18, since the same may be easily lifted from the drive shafts and removed through the open bottom of the chamber. These trays, therefore, may be easily removed and new ones or ones having a different size wire mesh bottom be substituted therefor.

It is apparent that the specific illustrations shown and described have been given by way of illustration and not by way of limitation and that the structure above described is subject to a wide variation and modification without departing from the scope or intention of the invention, all of which variations and modifications are to be included within the scope of the present invention.

What is claimed is:

1. Apparatus for separating a metal or alloy having a low melting point from one having a higher melting point comprising a furnace chamber having a discharge end with an opening in the lower portion thereof and an intake end opposite said discharge end with an opening in the upper portion thereof, a heating source in the upper portion of the discharge end of said chamber, metal feeding means on the intake end of said chamber substantially in alignment with said heating source and communicating with said intake opening, said metal feeding means being adapted to receive heat from said heating source to melt said metal or alloy therein having a low melting point before it enters said furnace chamber, a plurality of shaker trays each having a foraminous bottom sloping downwardly from said intake opening to said discharge opening, and a vibrating mechanism adapted to act simultane-

ously on each of said shaker trays adjacent both ends thereof to impart a vigorous vertical up and down movement simultaneously to both ends to jar said trays and separate the molten metal from the non-molten metal and induce lateral progression of the non-molten metal through the furnace chamber.

2. Apparatus for separating a metal or alloy having a low melting point from one having a higher melting point comprising a furnace chamber formed by a hood open at the bottom, a discharge end closing one end of said hood with an opening in the lower portion thereof, an intake end closing the opposite end of said hood with an opening in the upper portion thereof, a heating source in the upper portion of the discharge end of said chamber, metal feeding means on the intake end of said chamber substantially in alignment with said heating source and communicating with said intake opening, said metal feeding means being adapted to receive heat from said heating source to melt said metal or alloy therein having a low melting point before it enters said furnace chamber said metal feeding means comprising a container for metal to be fed to said furnace chamber having a bottom sloping toward the discharge end of said furnace, the container being mounted for reciprocal movement in relation to said chamber, a plurality of shaker trays each having a foraminous bottom sloping downwardly from said intake opening to said discharge opening, and a vibrating mechanism adapted to act simultaneously on each of said shaker trays adjacent both ends thereof to impart a vigorous vertical up and down movement simultaneously to both ends to jar said trays and separate the molten metal from the non-molten metal and induce lateral progression of the non-molten metal through the furnace chamber.

3. Apparatus for separating a metal or alloy having a low melting point from one having a higher melting point comprising a furnace chamber formed by a hood open at the bottom, a discharge end closing one end of said hood with an opening in the lower portion thereof, an intake end closing the opposite end of said hood with an opening in the upper portion thereof, a heating source in the upper portion of the discharge end of said chamber, metal feeding means comprising a container for metal to be fed to said furnace chamber having a bottom sloping toward the discharge end of said furnace, the container being mounted for reciprocal movement in relation to said chamber, means at the forward end of said container to govern the rate of flow of the metal into the furnace said flow governing means also being adapted to admit heat into said container from said heating source to melt said metal or alloy therein having a low melting point before it enters said furnace chamber, a plurality of shaker trays each having a foraminous bottom sloping downwardly from said intake opening to said discharge opening, connecting means connecting said metal container with the shaker tray adjacent said intake opening, and a vibrating mechanism adapted to act simultaneously on each of said shaker trays adjacent both ends thereof to impart a vigorous vertical up and down movement simultaneously to both ends to jar said trays and separate the molten metal from the non-molten metal and also impart a vibrating movement to said container through said connecting means thereby inducing lateral progression of the non-molten metal from the container through the furnace chamber.

4. Apparatus for separating a metal or alloy having a low melting point from one having a higher melting point comprising a furnace chamber formed by a hood open at the bottom, a discharge end closing one end of said hood with an opening in the lower portion thereof, an intake end closing the opposite end of said hood with an opening in the upper portion thereof, a heating source in the upper portion of the discharge end of said chamber, metal feeding means on the intake end of said chamber substantially in alignment with said heating source and communicating with said intake opening, said metal feeding means being adapted to receive heat from said heating source to melt said metal or alloy therein having a low melting point before it enters said furnace chamber, a plurality of shaker trays each having a foraminous bottom sloping downwardly from said intake opening to said discharge opening, a vibrating mechanism for said shaker trays comprising a plurality of cam shafts extending transversely of said furnace chamber adjacent the opposite end of each of said trays, polygonal-shaped cams on said shafts, said shaker trays resting upon said cams, means on said trays to limit longitudinal movement thereof, driving means to rotate said cam shafts thereby imparting simultaneously at both ends of said trays a vigorous vertical reciprocating movement to separate the molten metal from the non-molten metal and induce lateral progression of the non-molten metal through the furnace chamber.

5. Apparatus for separating a metal or alloy having a low melting point from one having a higher melting point comprising a furnace chamber, a chute inclined from one end of said chamber to the opposite end, said chute having a foraminous bottom, a vibrating mechanism for said chute comprising a plurality of cam shafts extending transversely of said furnace chamber adjacent the opposite end of said chute, polygonal-shaped cams on said shafts, said chute resting on said cams, means on said chute to engage said cam shafts and limit longitudinal movement of the chute, driving means to rotate said cam shafts thereby imparting simultaneously at both ends of said chute a vigorous vertical reciprocating movement to separate molten metal from non-molten metal and induce lateral progression of the non-molten metal through the furnace chamber.

6. Apparatus for separating a metal or alloy having a low melting point from one having a higher melting point comprising a furnace chamber, a chute inclined from one end of said chamber to the opposite end thereof, said chute comprising a plurality of shaker trays each having a foraminous bottom therein, said trays being mounted in cascade and disposed in relation to one another so as to provide a drop between successive trays, a vibrating mechanism for said shaker trays comprising a plurality of cam shafts extending transversely of said furnace chamber adjacent the opposite ends of each of said trays, polygonal-shaped cams on said shafts, said shaker trays resting upon said cams, means on said trays to loosely engage an adjacent cam shaft and limit longitudinal movement of the trays, driving means to rotate said cam shafts thereby imparting simultaneously at both ends of each of said trays a vigorous vertical reciprocation to separate the molten metal from the non-molten metal

and induce lateral progression of the non-molten metal through the furnace chamber.

7. Apparatus for separating a metal or alloy having a low melting point from one having a higher melting point comprising a furnace chamber, a chute inclined from one end of said chamber to the opposite end thereof, said chute comprising a plurality of shaker trays each having a foraminous bottom therein, said trays being mounted in cascade and disposed in relation to one another so as to provide a drop between successive trays, metal feeding means comprising a container for metal to be fed to said furnace chamber, one end being pivotally mounted outside of said chamber, a bottom on said container sloping from the outer end and entering said furnace chamber, said bottom resting upon the uppermost tray of said chute, a vibrating mechanism for said shaker trays comprising a plurality of cam shafts extending transversely of said furnace chamber adjacent the opposite ends of each of said trays, polygonal-shaped cams on said shafts, the bottom of said shaker trays engaging said cams, the said trays being supported thereby, means on each of said trays loosely engaging a cam shaft adjacent thereto to limit longitudinal movement of said tray, driving means to rotate said cam shafts thereby imparting simultaneously at both ends of each of said trays a vigorous vertical reciprocating movement to separate molten metal from non-molten metal and also impart a vibrating movement to said metal container thereby inducing lateral progression of the non-molten metal from the container through the furnace chamber.

8. Apparatus for separating a metal or alloy having a low melting point from one having a higher melting point comprising a heating chamber open at the bottom, a discharge opening in the lower portion of one end of said chamber, an intake opening in the upper portion of the opposite end of said chamber, a heating source in the discharge end of said chamber, a metal container in the opposite end thereof and adjacent said heating source said container being mounted for reciprocal movement in relation to said chamber, feed regulating and heat admitting means at the forward end of said container, a plurality of shaker trays each having a foraminous bottom sloping from said intake opening to said discharge opening, said trays being mounted in cascade and disposed in relation to one another so as to provide a drop between the successive trays, connecting means connecting said metal container with one of said shaker trays so that said container is responsive to the vibration of said shaker trays, a vibrating mechanism for said shaker trays comprising a plurality of cam shafts extending transversely of said furnace chamber adjacent the opposite ends of each of said trays, polygonal shaped cams on said shafts, said shaker trays resting on said cams, means on each of said trays engaging a cam shaft to limit longitudinal movement of said tray, driving means to rotate said cam shafts and impart a vibrating movement simultaneously at both ends to said trays and to said container to separate molten metal from non-molten metal and induce a lateral progression of the non-molten metal from the container through the furnace chamber.

WILLIAM B. COHEN.
